UNITED STATES PATENT OFFICE.

GEORGE W. MCGILL, OF NEW YORK, N. Y.

DESIGN FOR A PAPER-FASTENER.

SPECIFICATION forming part of Design No. 21,112, dated October 13, 1891.

Application filed September 12, 1891. Serial No. 405,540. Term of patent 14 years.

To all whom it may concern:

Be it known that I, GEORGE W. MCGILL, a citizen of the United States, residing at Riverdale, New York, in the county of New York and State of New York, have invented and produced a new and original Design for Paper and other Fasteners, of which the following is a specification.

This design has for its object to provide a novel and ornamental paper or other fastener; and it consists in a fastener provided with an elliptical head having a continuous or unbroken convex upper surface and a flattened lower surface, from the center of which extend two rectilinear superimposed prongs.

The design is illustrated by the accompanying drawings, in which—

Figure 1 is a perspective view looking at the upper surface of the fastener. Fig. 2 is a similar view looking at the lower surface of the same, and Fig. 3 is a top plan view.

In the drawings, the numeral 1 indicates the

elliptical head, having a continuous or unbroken convex upper surface 2 and a flattened lower surface 3, from the center of which extend two flat rectilinear superimposed prongs 4 and 5, of different length.

The design provides a novel and ornamental paper or other fastener, which presents a striking and characteristic appearance.

What I claim is—

The design for a paper or other fastener having an elliptical head provided with a continuous or unbroken convex upper surface and a flat lower surface from the center of which extend two rectilinear superimposed prongs, substantially as shown and described.

In testimony whereof I have hereunto set my hand and affixed my seal in presence of two subscribing witnesses.

GEORGE W. MCGILL. [L. S.]
